UNITED STATES PATENT OFFICE

2,664,679

ATTACHMENT FOR TRIMMING THE
TREADS OF WHEELS

Daniel Allcott Kelly, Milwaukee, Wis., assignor
to The Prime Manufacturing Company, Mil-
waukee, Wis., a corporation

Application January 5, 1952, Serial No. 265,109

3 Claims. (Cl. 51—255)

1

This invention appertains to railroads, and more particularly to means for maintaining the proper contour of the wear surfaces of wheels of freight and passenger cars, locomotives, etc., while the cars etc. are in service.

In railroading, it is customary, at periodic and stated intervals, to temporarily withdraw locomotives, both steam and diesel, from service, and to give such locomotives a thorough and complete check and overhauling. The active surfaces of wheels, both treads and flanges, are subjected to varying conditions of wear and the truing and maintenance of the wheels has caused great difficulties and problems to railroads. The wheels are constantly examined, and their peripheries gauged for uneven wear, both by the railroads and government inspectors. In many instances, locomotives have to be withdrawn from service on account of wear or change of proper contour of their treads and flanges, before the locomotive is due for its periodic overhauling, resulting in disruption of planned schedules.

It has heretofore been proposed to use grinding or abrasive brake shoes in an effort to maintain or true wheel tread and flange contours. In actual practice, the shoes are only active during brake applications and this fails to effectively grind the wheels. Further, the brake shoes are heavy and expensive to replace.

One of the primary objects of my invention, is to provide means independent of the brake rigging for engaging the periphery of a wheel at the proper place and with a constant, correct pressure for efficiently grinding off desired portions of the tread or flange, as the case may be, to restore proper peripheral contour.

Another salient object of my invention, is to provide a carrier for detachably receiving a plurality of grinding blocks, the construction of the carrier and blocks being such that any desired combination of blocks can be had for grinding off only certain portions of the tread and flange, or for grinding off the entire surface of the tread and flange to efficiently restore or true full wear contour where necessary.

A further object of my invention is to provide a carrier in which the grinding blocks can be readily removed and replaced when worn, and for obtaining different combinations of grinding areas and various types of grinding elements, i. e., fine, coarse, etc.

A further important object of my invention is to provide means for resiliently urging the grinding or abrasive blocks into engagement

2

with the wheel, so that the wheel and blocks can move up and down incident to the travel of a locomotive, or other car, means being provided for adjustably setting the tension of the spring or resilient means, so that the grinding blocks will engage the periphery of the wheel with a desired, selected pressure.

Another, further object of my invention is the provision of means for holding the grinding surface perfectly square with the flange of the wheel during the movement of the grinding blocks and carrier incident to the movement of a wheel.

A still further object of the invention is the provision of means for limiting the downward or inward movement of the carrier and blocks toward the wheel to prevent injury of parts, should the blocks become unduly worn before replacement.

With these and other objects in view, the invention consists in the novel construction, arrangement and formation of parts, as will be more fully described and claimed, and illustrated in the accompanying drawings, in which drawings,

Figure 1, is a fragmentary side elevational view of a locomotive truck, with parts thereof broken away and in section illustrating my novel truing or trimming device incorporated therewith and engaging the periphery of a wheel.

Figure 2, is a side elevational view of my wheel truing or trimming device connected to the truck of a locomotive, parts of the appliance being shown broken away and in section to illustrate structural detail.

Figure 3, is a top plan view of the appliance with parts thereof broken away and in section.

Figure 4, is a transverse sectional view through the mounting bracket, the section being taken on the line 4—4 of Figure 2.

Figure 5, is a sectional view through the carrier and abrasive blocks, the section being taken on the line 5—5 of Figure 2, looking in the direction of the arrows.

Figure 6, is a longitudinal sectional view through the carrier and the grinding blocks, the section being taken on the line 6—6 of Figure 5, looking in the direction of the arrows.

Figure 7, is a transverse sectional view through the carrier, taken on the line 7—7 of Figure 6, looking in the direction of the arrows.

Figure 8, is a view similar to Figure 6, and showing a combination of grinding or abrasive blocks for truing the entire periphery of a wheel.

Figure 9, is a view similar to Figure 8, but

3 showing a different arrangement of grinding blocks.

Referring to the drawings in detail, wherein similar reference characters designate corresponding parts throughout the several views, the letter A generally indicates my attachment for truing or grinding the periphery of a wheel W, constituting a part of a locomotive truck T.

The locomotive truck T can be of any type now in common usage in railroads, and includes a frame 10, having pedestals 11. The truck T, also carries the brake rigging B.

The wheel W is also of the type now found in common use and can either have an integral rim or a removable rim. The rim includes a tread 12 and a flange 13. The tread 12 and the flange 13 have a definite contour according to railroad and government specifications. If the tread or flange becomes worn or uneven, and out of this specified contour, then it is necessary to true the periphery of the wheel to the specified contour. The periphery can be ground down to a certain limit after which a new wheel is required or a new rim or tire, as the case may be. As heretofore brought out, this invention relates to means for trimming or truing a locomotive wheel to restore desired contour until the wheel has been ground or worn down below the specified limit of rim fitness.

My wheel trimming or truing attachment A is mounted upon a desired part of the wheel truck frame 10, preferably above the pedestal 11 and the brake rigging B, and includes a U-shaped supporting bracket 14, welded or otherwise secured to the desired part of the frame 10. The bracket 14, includes side legs or walls 15, the upper ends of which are connected by a cross-bar 16. Rockably mounted on the bracket 14 between the legs 15, is a swinging arm or lever 17. A pivot bolt or pin 18 supports the arm 17 and the pivot pin or bolt extends through slots 19, formed in the legs 15 of the bracket. The slots 19 allow slight lateral shifting of the arm or lever 17. The outer end of the arm has welded, or otherwise secured thereto, the carrier 20 for a plurality of grinding or abrasive blocks 21. The carrier 20 can be cast into the desired shape, or as shown, can consist of a top plate 22 having welded at its side edges, depending guide rails or tracks 23. The outer end of the carrier also has welded or otherwise fastened thereto and to the side tracks 23, an end bar 24, for a purpose, which will also appear. Intermediate rails or tracks 25 are welded, or otherwise fastened to the lower surface of the plate 22.

The abrasive blocks 21 are freely removable from the carrier 20 and their upper ends are provided with ribs 26 for sliding engagement with the tracks or rails 23 and 25. By referring to Figure 5, it can be seen that the blocks can be arranged in two longitudinal rows, and in any number of transverse rows of two blocks each, up to four rows. However, the number of longitudinal and transverse rows can be increased or decreased, as may be desired. The transverse rows of the blocks are preferably held slightly apart by spacer bars 27, which are also slid in the rails or tracks 23 and 25. In actual practice, a wheel is examined to determine the portions that have worn and blocks 21 are arranged in the carrier in the desired pattern to trim off the periphery of the wheel at the worn portion to restore the contour. As shown in Figure 8, the block arrangement can be such that the entire periphery of a wheel, including the

5 tread and flange, can be ground. Obviously, block arrangements can be had to only grind the tread or a portion thereof, or the flange. Where only a certain number of blocks are used, filler plates 28 can be utilized to fill a space normally occupied by a grinding block. It is to be also understood that the abrasive blocks can be of various, selected characters, i. e., fine, coarse, etc.

10 The grinding blocks and the spacer bars 27 and the filler plates 28, as the case may be, can be detachably held in the carrier 20, in any preferred way. As illustrated, a follower cross-bar 29 is placed at the end of the carrier remote from the end bar 24 and this follower bar 29, is provided with pusher lugs 30 for engaging against end abrasive blocks. The side rails or tracks 23 have formed thereon laterally extending ears 31. Bolts 32 extend through the ends 15 of the pusher bar 29 and the ears 31, and by adjusting the bolts, the pusher bar or its lugs 30 can be brought into tight contact with adjacent abrasive blocks 21, so as to force the opposite end abrasive blocks against the end bar 24. By removing the pusher bar 29, the blocks or desired block, or blocks, can be removed.

15 One of the important features of the invention is the provision of means for resiliency urging the carrier 20 and the abrasive blocks 21 toward the periphery of the wheel, and to accomplish this, I provide a spring 33 built up of a series of leaves. The leaves are firmly held together by clamping plates 34 and 35. Suitable bolts 36 extend through the plates 34 and 35 and through the leaves of the spring 33. The inner end of the spring is rockably mounted upon a pivot pin 38 carried by the legs 15 of the bracket 14. The outer end of the spring 33 bears against a rounded bearing bar 39 rigidly attached to the upper surface of the arm or lever 17 adjacent to its outer end.

20 Suitable means is provided to hold the spring 33 down against the carrier 20 with the desired pressure. As illustrated, a machine screw 40 is threaded through the cross-bar 16 of the bracket 14, and by turning this screw down different distances against the spring 33, or its clamping plate 34, the spring can be held with selected tension against the bearing bar 39.

25 One of the important features of the invention is that the grinding surfaces of the blocks 21 are held perfectly square with the flange of a wheel irrespective of the movement of the wheel during travel.

30 As the abrasive blocks become worn, the same are replaced with new blocks, and if the blocks become unduly worn before replacement, means is provided for limiting the downward swinging movement of the carrier 20 and the arm or lever 17 toward the periphery of the wheel. This means may merely consist of a set screw 41, carried by a cross-plate 42, welded or otherwise secured to the base of the bracket 14. The set screw 41 can be adjusted toward or away from the arm or lever 17, and can be held in its adjusted position by a second set screw 43, also threaded into the member 42.

35 While I have brought out that the device is particularly adaptable for truing locomotive wheels, it is to be understood that the device is also adaptable for trimming the wheels of freight and passengers cars, and the like.

40 From the foregoing description, it can be seen that I have provided an effective attachment independent of the brake rigging for truing the periphery of locomotive wheels of a type found in

common use and that with the attachment any desired combination of abrasive blocks can be had for trimming off only portions of the tread or flange of a wheel.

Changes in details may be made without departing from the spirit or the scope of this invention, but what I claim as new is:

1. An attachment for trimming and truing the periphery of a car wheel while the car is in motion and the wheel is rotating comprising a bracket adapted to be secured to a car truck adjacent to a car wheel, an arm pivotally secured to the bracket, a carrier on the outer end of said arm, a plurality of abrasive blocks detachably mounted in the carrier, spring means carried by the bracket engaging the arm normally urging the carrier and the blocks toward the periphery of a wheel, and means adjustably carried by the bracket engaging said spring means for increasing and decreasing the tension of the spring according to the adjustment of said last named means.

2. An attachment for trimming and truing the periphery of a car wheel as defined in claim 1, and means on said bracket disposed in opposing relation to the adjustable means for tensioning the spring and arranged in the path of said arm for limiting the swinging movement of the carrier and blocks toward the wheel.

3. An attachment for trimming and truing the periphery of a car wheel while the car is in motion and the wheel is rotating comprising a

10 bracket adapted to be secured to a car truck adjacent to a car wheel, an arm pivotally secured to the bracket, a carrier on the outer end of said arm, a plurality of abrasive blocks detachably mounted in the carrier, a leaf spring pivotally mounted on the bracket above the arm and extending longitudinally of the arm, and means adjustably carried by the bracket and engaging the spring for increasing or decreasing the tension of said spring.

DANIEL ALLCOTT KELLY.
